Primary Examiner — T Chase Nelson(74) Attorney, Agent, or Firm — Banner & Witcoff, Ltd.(57) CLAIM

The ornamental design for a shoe as shown and described.

DESCRIPTIONFIG. 1 is a bottom view of a shoe showing my new design; and,FIG. 2 is a bottom front perspective view thereof.
The broken line immediately adjacent to the forward edge of the photographic area defines a bound of the claimed design and forms no part thereof. The broken lines depicting the remainder of the shoe form no part of the claimed design.1 Claim, 2 Drawing Sheets(56)
